UNITED STATES PATENT OFFICE

JOHN MOSCINI, OF PATERSON, NEW JERSEY, ASSIGNOR TO MULTI-COLOR PRESS CORPORATION, OF PATERSON, NEW JERSEY, A CORPORATION OF NEW JERSEY

PRINTING PRESS

Application filed October 29, 1929. Serial No. 403,144.

This invention relates to that class of printing presses in which, given the frame, a platen and a type supporting structure therein, one of which is reciprocatory toward and from the other, the means to apply ink to the type passes between the type and platen and also around that part of said structure which immediately supports the type. I aim to simplify the construction of a printing press of this type, reduce the power necessary to drive it, increase its efficiency and reduce the likelihood of its getting out of order and render it possible to make readily any adjustments, repairs or the like which may be necessary, and in particular to construct the press so that it may be efficiently operated with one or more similar presses when the printing to be done requires several impressions to be effected at given intervals on a strip, as in two-color or multi-color printing.

In the drawings,

Fig. 1 is a side elevation showing two presses embodying the invention, in tandem;

Fig. 2 is a front elevation of the left-hand press, certain parts being removed;

Figs. 3 and 4 are sections substantially on lines 3-3 and 4-4, respectively, Fig. 2, certain parts being omitted;

Fig. 5 is a diametric section of one of the gears 12, with the inking rollers in fragmentary elevation;

Figs. 6 and 7 are side and front elevations of the paper-feed mechanism; and

Figs. 8 and 9 illustrate an adjustable fulcrum-support for a certain lever 68, Fig. 8 being a section through the lever and the fulcrum support on line 8-8, Fig. 9, and Fig. 9 being a face view of said fulcrum-support.

Except as hereinafter indicated, both presses shown in Fig. 1 are alike, so the following description of one will serve for both.

The main frame comprises a pair of uprights 1 rigidly connected near their bases by the cross-frame 2 which has a vertical opening 3 forming a guideway for the vertically reciprocating plunger (to be described) and also has on opposite sides the projections 4 and 5, one to afford a bearing and the other a shelf. The said plunger, 6, appears U-shaped as seen in Fig. 2, but each upstanding

leg thereof has opposite arms 6a and 6b so arranged that as seen in Figs. 1, 3 and 4 the plunger appears cross-shaped; the lower or web portion 6c of the plunger (narrower than the upper portion) is movable vertically in the guideway 3 and in an opening forming a horizontal guideway 7 therein slides a block 8 bored to receive an eccentric 9 fixed on a horizontal shaft 10 which may be driven in any way and may be journaled in the cross-frame 2 and in a standard 11 (Fig. 1). When the shaft is rotated the plunger reciprocates vertically in the main frame.

Fixed in the legs of the plunger is a horizontal shaft 12 on which is keyed a cylindrical drum 13 which is flattened as at 13a-13b at the top and bottom, except at the ends at the bottom which conform to the cylinder of the drum. On the shaft revolve two gears 14, they being coupled to rotate in unison by a shaft 15 journaled in the mentioned arms 6a of the plunger and having pinions 16 in mesh with the gears. Shaft 15 is driven from shaft 10 through a telescopic shaft 17 (whose members are in effect splined together by one having a slot 17a receiving a pin 17b in the other, Fig. 3) and bevel gearing 18 connecting shafts 15 and 17 and bevel gearing 19 connecting shafts 10 and 17; the lower member of shaft 17 is journaled and supported in the projection 4 of the cross-frame 2 and the upper member in a yoke 20 (shown only in Fig. 2) which is hung from shaft 15. The telescopic shaft 17 permits the drive to be transmitted to the two gears notwithstanding their reciprocation with the plunger. On the flat 13a of the drum, whose cylindrical surface forms the ink distributing surface, as will appear, is adapted to be placed the type 21. The gears when in rotation cause inking rollers of rubber or equivalent material to roll around the drum 13 in rolling contact with its distributing and type surfaces, as follows:

There are in the present case two sets of these inking rollers, 22, diametrically opposite each other. Each inking roller in each set has its shaft 23 movable in radial slots 24 in the two gears and urged toward the axis of the gears by springs 25 attached to 100

the gears; on the shaft of each roller is a pair of hard (as steel) rolls 26 which run on the end or more completely cylindrical portions of the drum 13. As the inking rollers are moved around the drum by the gears they travel in a cylindrical path except at the top, where they follow the planiform face of the type; the flat 13b at the bottom and between the ends of the drum affords desirable clearance for cleaning each set of inking rollers (then held spaced from such flat because their rolls 26 are resting on the cylindrical ends to wit, flanges 13c of the drum) on bringing the gears to rest with such roller set opposite said flat. The slots 24 are open at their outer ends to permit each roller to be removed for repairs or replacement, as upon shifting the same lengthwise until one end clears the rim portion 14a (Fig. 5) of the gear 12.

A pair of transverse shaft-like eccentrics 27 have bearings in the uprights 1 above the drum and cranks 28 thereon are connected by a link 29 so that they rock together; either 25 crank may have a handle 30. On one of these shafts is fulcrumed the carrier 31 for the platen 32 having a fork 32a and on the other is a sleeve 33 having a radial headed screw 33a adapted to be received by the fork, 30 which may then be clamped to the sleeve by the screw. The carrier and sleeve form the platen frame which may be raised from the type by turning the two eccentrics 27; such frame is further capable of disruption upon 35 loosening screw 33a and turning the sleeve on its eccentric 27 sufficiently to permit the carrier part of the frame to be swung up on the other eccentric as an axis, as when it is necessary to remove the platen facing and 40 substitute another.

On a plate 34 secured on projection 5 of the cross-head 2 is an upstanding transverse wall 35 having an inclined top to which is secured an elastic blade 36 whose lower edge 45 is bent off and bears longitudinally of and against a roller 37, the blade and roller together forming with end walls 35a an ink-font; the pressure of the blade-edge against the roller may be varied by an adjusting screw 38 tapped into wall 35, such adjustment determining the amount of ink which will pass the blade and remain adhering to the roller's surface. Rotation of the font roller 37 is effected by providing its shaft 37a which is journaled in the end walls 35a, with a ratchet 39 with which is engaged a pawl 40 pivoted to a lever 41 fulcrumed on said shaft and connected with one of a pair of brackets 42 on the arm 6b of the plunger 6 by a link 43. Due to the motion of said plunger the ink is constantly fed from the font, being distributed over the periphery of the roller 37. In the arms 6b is journaled the 55 shaft of an ink-feed roller 44 which has a pinion 45 in mesh with one of the gears 12

and to the periphery of which the ink is delivered from font roller 37 as will appear. When the inking rollers 22 pass this roller their rolls 26 ride over cams 46 on the drum 13, causing rolls 22 to be revolved by and thus take the ink from the ink-feed roller. The ink is transferred from the font roller to the ink-feed roller by a transfer roller 47 which is journaled in a pair of levers 48 fulcrumed in the brackets 42 and normally urged by 70 springs 49 connecting them with some part of the press, as the projection 5, to hold the transfer roller against the ink-feed roller, but adapted to be shifted, to move the transfer roller against the font roller 37 each time the plunger descends, thus to ink the transfer roller, by thereupon engaging stops 50 on the plate 34.

The supply of paper A to be printed is here shown as a roll 51 mounted on a shaft 52 journaled in brackets 53 on the frame of the right-hand press in Fig. 1. By means now to be described it is withdrawn from the roll step by step, being kept in a horizontal plane under the platens of the two presses by 85 suitable guide-rollers at 54. On brackets 55 on the frame of the left-hand press are mounted stands 56 in which and in blocks 57 slidable vertically therein are respectively journaled the feed-rolls 58 and 59, the blocks being subject to the downward pressure of springs 60 interposed between them and adjusting screws 61 in the stands. The paper A passes between these feed rolls. Roll 59 has fixed on its shaft a ratchet 62 and journaled on its shaft a member comprising a disk 63, carrying a pawl 64 spring-pressed against the toothed surfaces of the ratchet, and a pinion 65. This member is oscillated, so that the pawl will impart rotary advances to the roll in the direction to feed the paper A, by a rack 66 engaged with pinion 65, said rack being attached to a rod 67 suitably guided by the frame and pivotally connected to a lever 68 (Fig. 1) which has a fork engaged with the shaft of the ink-feed roller 44. So that the increments of advance of the paper may be varied the fulcrum of the lever is adjustable relatively to the lever thus (Figs. 1, 8 and 9): In a block 69 attached to the adjoining frame upright 1 is horizontally adjustable, by means of a set-screw 70, a block 71 which has the stud 72 affording the fulcrum for the lever swivelled therein. This stud is threaded and between a shoulder 73 thereof and a nut 74 screwed thereon the lever 68 may be clamped, the lever having a longitudinal slot 68a receiving the stud. Adjustment is effected by releasing nut 74, turning screw 70 to adjust the block 71 one way or the other and hence the stud or fulcrum in the slot of the lever, and then re-tightening the nut to clamp the lever to the stud. 110

There may be means to sever the paper strip on each printing impression. Thus 75 130

is a frame mounted on the brackets 55 and having a fixed knife 76 and a reciprocating knife 76' which is connected with levers 77 having links 78 depending therefrom and joined together by a bar 79 which rides on a cam 80 on the shaft 10.

The frames of the presses are mounted to slide toward and from each other on a bed 81, they having underneath racks 82 engaged by pins 83 either of which by a crank applied to its stud 84 may be turned to adjust each press toward and from the other (Fig. 1). To permit this adjustment shaft 10 is formed in two sections connected to rotate together by a coupling sleeve 85 on one in telescoped arrangement with the other, the latter being in effect splined to the sleeve, say by having a slot 86 receiving a pin 87 in the sleeve.

Operation: With shaft 10 in rotation the plunger reciprocates to cause the type to contact with the platen to print and the inking rollers are caused by the gears 14 to travel around the drum 13 to distribute the ink which they receive from the ink-feed roller 44 over the cylindrical portions of the surface of the drum and to ink the type. The flats 13a and 13b and the cylindrical or ink-distribution portions of the drum's surface occupy approximately equal or quarter sectors of the drum, wherefore the gearing is such that during that half of each cycle in which the plunger is retracted from the platen one or the other set of said rollers runs over the type and in the remaining half of the cycle said rollers run over said ink-distributing portions of the drum's surface. As each set of rollers reaches the ink-feed roller 44 it receives ink therefrom as explained, and each time the plunger rises roller 44 in turn receives ink from the transfer roller 47 which on the previous descent of the plunger received ink, as explained, from the font roller 37. Of course these operations apply to both presses. Meanwhile the feeding of the paper step by step and the severing thereof proceed as already fully explained, the paper being of course at standstill each time a printing impression occurs.

So far as I am aware I am the first not only to reciprocate the plungers of two presses of the class to which my invention appertains from a common shaft, as 10, but to provide for the adjustment of the presses toward and from each other. This latter is a valuable feature of my invention in that, in the case where the material being printed is in strip form, as A, and its increments of advance are equal to the end that the centers of the printed impressions will be equally spaced, and the press which effects the second impression (here the left-hand one) should do so in a definite relation to the impressions effected by the first (or right-hand) press, as in two-color printing, it makes it possible to obtain registry of the impressions of the two presses

although the spacing of the impressions for one strip to be printed may require to be different from that of another such strip.

Having thus fully described my invention what I claim is:

1. In combination, a frame, a platen therein, a structure arranged to reciprocate up and down in the frame toward and from the platen and including a drum having its axis substantially horizontal and also having its periphery formed in part by a printing face arranged to coact with the platen and in part as a distributing face, another structure carried by and revoluble around said axis and having means to ink said faces of said periphery, a revolving driver arranged under and having its axis substantially horizontal and crossing the first axis and also having an eccentric engaged with and adapted to reciprocate the first structure, and means to transmit rotation to the second structure from the driver while the first structure is reciprocated by the driver.

2. In combination, a frame, a platen therein, a structure arranged to reciprocate up and down in the frame toward and from the platen and including a drum having its axis substantially horizontal and also having its periphery formed in part by a printing face arranged to coact with the platen and in part as a distributing face, another structure carried by and revoluble around said axis and having means to ink said faces of said periphery, a revolving driver arranged under and having its axis substantially horizontal and crossing the first axis and also having an eccentric engaged with and adapted to reciprocate the first structure, and gearing connecting the driver and said means and including a transmission element revoluble on an upright axis and comprising telescoped members splined together and one of which is journaled in the frame and the other in said structure.

3. In a machine of the class described, the combination of a drum having a part of its periphery in one sector of the drum a printing face and in another sector having flanges spaced from each other lengthwise of the axis of the drum, the space between said flanges being in a zone coinciding with the printing face, a structure revoluble around the axis of the drum from the printing face to said flanges and an inking device arranged against the drum and movable with said structure in contact with said face and the flanges.

4. A printing mechanism including a frame, a platen therein, a structure arranged in the frame and including a drum having its periphery formed in part by a printing face arranged to coact with the platen. Means to cause reciprocation one toward the other as between the platen and said structure, ink-feed means arranged in the frame in spaced relation to the periphery of the drum, and an

other structure carried by the first structure and revoluble around the axis of the drum and including an inking roller arranged to pass between the drum and said ink-feed means 5 and movable to one or the other of them, said mechanism having means to move the roller to the ink-feed means when it passes the same and then to the periphery of the drum.

5. In combination, a frame, a platen there-
10 in, a structure arranged in the frame and in-
cluding a drum having its axis substantially
parallel with the platen and also having its
periphery formed in part by a printing face
arranged to coact with the platen, means to
15 cause reciprocation one toward the other as
between the platen and said structure,
another structure carried by the first struc-
ture and revoluble around the axis of the
drum and including an inking roller yield-
20 ingly held in rolling contact with said per-
iphery, and ink-feed means arranged in the
first structure outward of the path of move-
ment of the roller with the second structure,
said first structure having means to cam the
25 roller against said ink-feed means.

6. In combination, a frame, a platen there-
in, a structure arranged in the frame and in-
cluding a drum having its axis substantially
parallel with the platen and also having its
periphery formed in part by a printing face
arranged to coact with the platen, means to
30 cause reciprocation one toward the other as
between the platen and said structure,
another structure carried by the first struc-
ture and revoluble around the axis of the
drum and including an inking roller yield-
35 ingly held in rolling contact with said per-
iphery, and revoluble ink-feed means ar-
ranged in the first structure outward of the
path of movement of the roller with the sec-
ond structure and rotated by the latter struc-
40 ture, said first structure having means to cam
the roller against said ink-feed means.

7. In a printing press, the combination of
45 a frame, ink-supplying means in the frame,
a structure arranged to reciprocate in the
frame toward and from the first means, a ro-
tary member revoluble in said structure and
having its periphery adapted to be inked, ink-
50 transfer means movable in said structure
back and forth into contact with said member
and first means in alternation, and means to
cause the transfer means to move in said
structure toward the supply means when said
55 structure moves toward the latter and from
the supply means when said structure moves
from the latter.

8. In a printing press, the combination of
60 a frame, ink-supplying means in the frame,
a structure arranged to reciprocate in the
frame toward and from the first means, a ro-
tary member revoluble in said structure and
having its periphery adapted to be inked, a
65 lever movable back and forth in said struc-
ture, an ink-transfer roller revoluble in the

lever and movable with the same into contact
with said member and first means in alterna-
tion, and means to move said lever first one
way and then the other when said structure
in reciprocating moves, respectively, in one 70
direction and then in the other.

9. The combination of a frame, a recipro-
cating structure therein, said frame and
structure having, coactive with each other, a
printing face and a platen, a sheet feed 75
means, means to transmit actuation from said
structure to said feed means including a lever,
and a fulcrum-support for the lever adjust-
able on the frame lengthwise of the lever.

10. In a printing press, the combination of 80
a frame, a structure reciprocatory therein
and having a printing face, a platen frame
operatively opposed to said face, a pair of
eccentrics journaled on parallel axes in the
first frame and supporting the platen frame 85
and means connecting the eccentrics for ro-
tation in unison, said platen frame being
adapted to receive the platen and having the
portion thereof supported by one eccentric
disconnectively connected with the portion 90
thereof supported by the other eccentric,
whereby the first-named portion and the
platen may be swung on the first-named sup-
porting eccentric as a pivot out of coactive
relation to said printing face. 95

In testimony whereof I affix my signature.
